HOLDER FOR A TELEPHONE HANDSET

Karl L. Krattenstein, Hotel Somerset,
150 W. 47th St., New York, N.Y.

Filed June 9, 1965, Ser. No. 85,643

Term of patent 14 years

(Cl. D26—14)

FIG. 1 is a side elevational view of a holder for a telephone handset, showing my new design;

FIG. 2 is a side elevational view, to an enlarged scale;

FIG. 3 is a front elevational view, to the same scale as FIG. 2;

FIG. 4 is a rear elevational view, to the same scale as FIG. 2;

FIG. 5 is an opposite side elevational view, to the same scale as FIG. 2;

FIG. 6 is a top plan view, to the same scale as FIG. 2; and

FIG. 7 is a bottom plan view thereof, to the same scale as FIG. 2.

The dominant features of my design are shown in solid lines in the drawing. Portions of the supporting stand shown in broken lines in FIG. 1 have been omitted from the remaining figures for convenience of illustration. The handset shown in broken lines in FIGS. 1, 2, and 4 is for illustrative purposes only.

I claim:

The ornamental design for a holder for a telephone handset, as shown and described.
